ALUMINUM CREEL

Fletcher M. McDonald, Portland, Oreg.

Application February 3, 1947, Serial No. 726,156

4 Claims. (Cl. 220—19)

1

My invention relates to a fishing basket made of light weight material, preferably aluminum wire of two sizes, heavy and light, in order to obtain an article combining light weight with great rigidity. Accordingly I use for the frame work upright struts and cross wires of a heavy aluminum wire about 0.092 inch in diameter while for the interwoven strands I use a light aluminum wire about 0.061 inch diameter.

The basket is of general kidney shape in order to cling snugly over the hip of the sportsman and is larger at the bottom than at the top with the sides tapering upwardly. A lid covers the entire top with the exception of a narrow opening in the middle, thru which fish that have been caught are dropped into the basket without lifting the lid.

Some of the advantages of this creel are, light weight, ease of cleaning like any household utensils, rustproof, and having porous walls, providing good ventilation.

These and other advantages and objects of my invention will be explained in the subjoined description with the aid of the attached drawing, wherein:

Figure 1 is a perspective view of the skeleton or frame work of the basket, constituting the warp;

Figure 2 is a front elevation of the basket or creel with the lid open;

Figure 3 is a bottom plan view of the creel;

Figure 4 is a fragmentary rear view of a corner thereof;

Figure 5 is a perspective view of the form over which the basket is built;

Figure 6 is a fractional view showing the interweaving of warp and weft;

Figure 7 shows the contours of the three types of warp wires.

Like numerals denote the same details in the different views.

This basket is constructed in its entirety preferably of aluminum wire in two sizes, namely for the warp or struts a diameter of about 0.092 inch is preferred to insure rigidity of the frame work; and a smaller size aluminum wire of 0.061 inch in diameter for the weft 11.

The first step in manufacturing this wire basket is, to provide a rigid form 12 of wood, see Figure 5. The bottom surface 13 of the form has kidney contour with concave rear edge 18 and convex

2

front edge 19, while the top surface 14 has half moon shape with a straight rear edge 15 and an outwardly arched front edge 16 melding into the rear edge 15 with rounded ends 17. The top surface 15 is of smaller area than the bottom surface 13. The body of the form accordingly tapers from the bottom 13 to the top 15 with an outward curvature in front and on the ends, while the rear face of the form has an inward bulge towards each end. This form is built of solid wood and cut into three or four sections to facilitate removal, after the basket has been built around it.

The next step in manufacturing is now to place the form 12 upside down that is with the surface 15 uppermost on a table and to build the skeleton or frame work 22 over it as seen in Figure 1. Pieces of the heavy aluminum wire are now cut to required length providing the warp 22 for the weave. All of these warp lengths are now placed 20 with their middle portions 23 across the bottom, surface 13, slanting slightly horizontally to the rear and then bent down over each edge 18 and 19 to form the upright struts or ribs 24 which each terminate with a hook portion 26 adapted 25 for engagement with the top edge of the basket. As best seen in Figure 1, the warp members A have the shape of letter U, wherein the middle portion 23 forms the bottom brace, the upright portions 24 form the struts or ribs, one with a 30 convex, the other with a concave bend; the warp member B has both its ribs or struts 24a with convex bends, but the brace 23a is V-shape. Warp member C, which is L-shape has a single 35 upright portion or rib 24b and a short brace 23b terminating with a hook or eye 23c.

One of these warp members C is placed at each end of the form, while two warp members B are placed next thereto from the ends and between them, the space is filled with ten, more 40 or less, of the A warp members. However, in the very middle, between the innermost pairs of warp members A is placed one warp member C, with the short brace 23b on the bottom 13 radially from the rear edge 18 of the form, and the rib 24b along the rear side of the form.

The next step is now to build the bottom of the basket over the form 12 while still standing upside down, with the warp clamped down thereon. Then six or more strands 27 are cut from 45 the lighter aluminum wire to constitute the central bottom weft, woven in and out between

3

the brace portions 23 of the warp members A and the ends 28 of the strands 27 are clinched over the V braces 23a at each end. This now forms the central portion of the basket bottom, see Figure 3. Around the central portion the rest of the kidney shaped bottom is now woven by the continuous weft 11 of light aluminum wires until the entire bottom surface is covered.

Thereupon the basket sides are constructed by continuing the weaving in and out of the light weft wire 11 between the uprights 24, 24a, 24b.

When the full height of the basket has been reached in this manner, the uppermost strand 31 is looped around each end of the ribs or struts 24 and the hooks 25 are then clinched over the loops along the convex top front edge at 31 of the basket.

The straight rear edge of the basket is formed in the same manner, but the struts or ribs 24 in that case extend beyond the top edge of the rear wall in order to engage the straight bottom rod 33 of the lid. Around the lid rod, which is straight and preferably also made of heavy aluminum wire, are clinched all the hooked ends 26 of the ribs 24, thereby providing hinges for the lid.

In Figure 4 is shown a corner of the rear wall of the basket, where a square aperture or small window 32 is indicated. This is formed by cutting a few of the weft strands 11 and clinching their ends around two adjacent ribs 24. There is one such window at each corner of the basket and by passing a leather strap with a clasp across the rear wall thru said windows, the basket may be carried with ease over the shoulder.

The lid is similarly constructed, as seen in Figures 1 and 2. It consists of a half-moon shaped frame of the same heavy aluminum wire, with a straight rear rod 33 and continuous therewith an arcuate front rod 35 of the same contour as the top front edge 31 of the creel or basket proper. As already stated the straight rod 33 together with the hooked ends 26 of the ribs 24 and 24a which are clinched over said rod, constitute the hinge connection between the lid and the basket. The space between each pair of adjacent hinges is filled by spacer rings 36 placed around the rear rod 33.

In the case of the lid, the warp consists of short pieces of struts 37 of different lengths also made of heavy aluminum wire. These struts 37 are spaced almost parallel to the straight rear rod 33 and the arcuate front rod 35, to both of which the hooked strut ends 38 are clinched, see Figures 1 and 4.

Parallel to the straight rod 33 the weft 42 of lighter aluminum wire is next woven in and out between the warp struts 37 lengthwise from end to end of the lid.

As indicated in the drawing a large window 40 is formed in the middle of the lid 41 by cutting the two middle struts 37, short and clinching their inner hooked ends at 43 around one or two of the parallel weft members 42.

These weft members 42 above and below said window 40 are continuous and are taken once or twice around the arcuate front rod 35 of the lid frame. But at the top, they are twisted several times around the same between the hook ends 44 of the struts so as to fill the space between each two adjacent struts.

A short leather strap 45 is attached between the two middle struts 37 on the arcuate frame rod 75

4

35. A buckle 46 for said strap is provided a short distance down the front side of the basket.

The construction of the bottom of the basket is shown diagrammatically in Figure 3. For clearness sake the strands 27 have been omitted in Figure 1.

It is to be understood that the invention as herein disclosed may be varied from the details described and shown without departure from the spirit of the subjoined claims.

I claim:

1. A fishing creel comprising a basket structure open at the top and made of woven light metal wire throughout, having a concave rear wall, a convex front wall, a flat bottom and a similarly woven flat lid adapted to cover said open top, the woven form of the walls and bottom providing warp and weft wires, the warp wires comprising a plurality of U-shaped frames each forming a bottom brace and upright front and rear ribs, said ribs terminating in hooked ends engaged around the uppermost weft wire at said top opening, the weft wires running in and out in horizontal layers around the basket between said ribs.

2. In a fishing creel, a frame structure comprising a plurality of substantially U-shaped units formed of wire, said units being in side by side relation and each having spaced front and rear members and a connecting bottom member, said frame further including similar end units of substantially U-form in which the connecting bottom member is V-shaped and positioned in a common plane with the bottom members of the first mentioned units, said spaced members of the U-shaped units each terminating in a turned back hook end, a plurality of wire strands extending transversely of and woven between the spaced members of the U-shaped units to form a fabric wall structure in which the side and bottom members of the U-shaped units form the warp and the said wire strands form the weft, the topmost strand being secured in certain of said turned back hook ends, and a cover of woven wire strands hingedly connected to others of the turned back ends at one side of the creel.

3. A fishing creel construction of the character stated in claim 2, with additional weft strands woven between the bottom members of 50 the U-shaped units and secured at their ends to the said V-shaped bottom members of the said end units.

4. A fishing creel comprising a frame structure made up of a plurality of vertical front, back 55 and side strands and bottom strands connecting the lower ends of pairs of vertical strands, said vertical and bottom strands constituting warp strands of a woven fabric, horizontal close laid weft strands of such fabric, means forming a locking coupling between the topmost weft strand and the top ends of the said front and side vertical strands, a cover comprising a frame portion and a woven filler therein, said cover frame portion having a straight back bar part, and means forming a hinge connection between the said back bar part of the cover frame and the top ends of the said back strands, said locking coupling being defined by a looped portion of the said weft top strand encircling the said front and side vertical strands and a downturned hook portion forming a part of the top ends of the said front and side strands and enclosing the said weft top strand.
